EDWARD LIND, OF BROOKLYN, AND DAVID FEIGENBAUM, OF JAMAICA, NEW YORK

COLLAR

Application filed September 5, 1929. Serial No. 390,456.

The present invention relates to collars and more particularly to soft collars of the double fold or turned down type, and aims to provide certain improvements therein.

5 Heretofore, various means and devices have been employed in an endeavor to insure in a soft collar, while being worn, its intended shape and neatness. These means and devices, which are conventionally formed of fabric, metal, composition and like elements are either permanently embodied in the parts of the collars to be stiffened or are removably positioned at the back or within pockets in the collar, and have met with more or less 10 approval. The principal reasons for the failure of the majority of said devices to gain favor are, difficulty in laundering, danger of loss or misplacement of the removable stiffening elements, too great rigidity and sharpness of the stiffening elements, and lack of 15 adaptability of said elements to conform to the natural contour of the neck and chest of the wearer.

According to the present invention, we 20 provide a novel stiffening means for soft collars which overcomes all of the objections aforementioned and which adds practically nothing to the cost of manufacturing collars without stiffening elements. This we 25 accomplish by permanently incorporating into the collar during the seaming operation, means for rendering the desired edges pliable and settable. Preferably this is done by sewing onto the edge of the collar simultaneously 30 with the operation of stitching together of the front, back and lining of the collar a tape or strip containing a fine non-rustable wire which is settable under the influence of slight force or pressure. The invention also embodies other features of novelty which will 35 be apparent from the detailed description which follows.

In the accompanying drawings wherein we have shown preferred embodiments of our 40 invention:

Figure 1 is a perspective view with parts broken away of a collar embodying our invention.

Fig. 2 is a greatly enlarged section taken 45 along the plane of the line 2-2 of Fig. 1.

Fig. 3 is a fractional perspective view of a collar showing a slight modification of the invention.

Fig. 4 is a perspective view of the stiffening element and the method of forming the 50 same.

Referring to the drawings, let A indicate a soft collar of the double fold or turned down type comprising an inner fold B and an outer fold C, each of which may consist 55 of a plurality of plies of fabric as is conventional with said collars. As herein shown, the outer fold C consists of three plies, namely, an inner ply D, an outer ply E and a lining ply F. In the making of these collars 60 the various plies of the outer fold are seamed or stitched together along the front and lower edges of the collar and are then turned inside out to provide a so-called "French" 65 seam.

According to the present invention, stiffening means are incorporated in the front edges of the collar and also if desired partially or completely around the lower edge. 70 These stiffening means are of a character which do not detract from the flexibility and pliability of the collar and at the same time render the edges wherein they are applied settable, that is, capable of being shaped to conform to any straight or curved contour. 75 The means which we prefer to employ for accomplishing this property of setability is a fine, soft non-rustable wire G, which may be incorporated into the edges of the collar 80 which it is desired to stiffen. As herein shown, this wire G is first secured to a tape or fabric strip H by sewing the wire therein with a line of stitching J, as best shown in Fig. 4. The stiffening strip thus obtained is then attached to the various plies of the 85 fold of the collar by a seam K, which seam also serves to unite the various plies together and constitutes one of the first seaming steps in the formation of the collar.

After this seaming operation the plies of the fold are turned and a second row of stitching L is sewed therethrough beyond the turned free edges of the plies as is conventional in collar manufacturing. In turning 90 the plies inside out, the wire in the edges 95

serve as a line of fold and are thereby positioned in the extreme edges of the collar.

Where only the stiffening means are to be applied to the front edges of the collar as shown in Fig. 1, the fabricated stiffening element with the wire therein may be first cut into strips of the desired length prior to stitching the same to the collar plies. Where the stiffening means are to extend also around

10 the lower edge of the collar, the fabricated stiffening strip may either be first cut into desired lengths or sewed to the plies from a roll of stiffening material and severed at the proper points. In either method of procedure it will be apparent that no additional seaming operation is required for incorporating the stiffening element into the collar. The only additional cost, which it will be appreciated is nominal, is that of the stiffening element per se.

A soft collar provided with the stiffening elements of the present invention we have found will enable the stiffened edges to conform to the natural contour of the neck and chest of the wearer, and should said edges accidentally become bent out of shape a passing of the fingers thereover accompanied by slight pressure will reset said edges to their intended shape. The style and neatness of

25 the collar while being worn can thus be readily preserved. We have also found that the stiffening element as hereinbefore described does not interfere with the laundering of the collar, but on the contrary gives to the collar

30 35 when laundered an added degree of smartness.

While we have shown and described certain preferred embodiments of our invention, we do not wish to be limited to the precise constructions disclosed, since it will be apparent to those skilled in the art that modifications thereof may be resorted to without departing from the spirit of the invention.

What we claim is:

40 1. A soft collar comprising a plurality of plies of fabric, an additional fabric strip within each front edge of the collar, a pliable, settable stiffening wire carried by said fabric strip, and said fabric strip together with its

45 50 stiffening wire being attached to the collar by the same seams which unite the plurality of plies of fabric of the collar.

2. A collar comprising a plurality of plies of fabric, one of which carries a pliable settable stiffening wire in one edge thereof, all of said plies of fabric being attached together by a common seam and said wires serving as a line of fold for turning the plies inside out, whereby said wire will be positioned in the

55 60 extreme edge of the collar.

3. A collar comprising a plurality of plies of fabric, an intermediate ply of fabric which carries a fine pliable settable wire in an edge thereof which is coincident with a front edge

65 70 of the collar, said wire carrying ply being at-

tached to the collar by the same seam which unites the plurality of plies of fabric together, and said wire serving as a line of fold for turning the plies inside out, whereupon said wire will be positioned in the extreme front edge of the collar.

In witness whereof we have hereunto signed our names.

EDWARD LIND.

DAVID FEIGENBAUM.
